TAPE APPLYING MACHINE

Walter P. Osgood, Malden, Mass.

Application April 2, 1937, Serial No. 134,566

17 Claims. (Cl. 12—51)

The present invention relates to taping machines which are used in the manufacture of shoes to apply tape to uppers and parts thereof.

In the manufacture of pumps it is often desirable to employ a one-piece vamp, at least from the tip line rearwardly, in which case it is necessary to perform the top-taping operation prior to the closing operation in which the rear edges of the one-piece vamp are closed at the heel thereby converting the vamp into a ring-like form, the flesh or unfinished face of which is bent concavely. During the top-taping operation heretofore the tape was applied to the vamp while it was in a sheet form. That is, a lineal length of tape was applied to a commensurate length of vamp. When, however, the vamp was closed in a ring-like form and provided with a concavely bent flesh or unfinished face, the tape, being the innermost ply thereof, became wrinkled objectionably.

The principal object of the present invention is to produce a taping machine which will convert the sheet material into the form it assumes when the work is closed or assembled upon the last and apply tape to the sheet material in its converted form.

To the accomplishment of this object a feature of the present invention contemplates the provision in a taping machine having means for supporting and feeding the grain or finished face of the work, of means for bending the flesh or unfinished face of the work concavely about an axis extending substantially normal to the line of feed and for applying tape to the bent face.

Broadly considered the feeding, bending and tape-applying means may be independent, each, however, cooperating with the means for supporting the work. It is preferred, however, to employ a single means which cooperates with the work-supporting means to feed the work, to bend the work and to apply tape thereto.

Preferably the principal feature of the present invention is embodied in a machine of the progressive feeding and tape-applying type and in consequence it is desirable that the bending means operate progressively during the feed and tape application.

In my Patent No. 1,899,051, February 28, 1933, I have disclosed a tape-applying machine having a tape-applying mechanism which operates periodically and a tape pull-off mechanism which operates non-periodically. In my patented machine the tape is pulled off the source of supply by a drum mounted upon the lever which operates the tape-applying mechanism. The drum

is provided with a ratchet which, in non-periodic manner, is engaged with a pawl mounted independent of the lever, whereby the combined oscillating and reciprocating movements of the lever causes the pawl through the ratchet to rotate the drum. The drum is heavy compared to the weight of the pawl.

Another object of the present invention is to simplify and improve the pull-off mechanism disclosed in my patented machine while retaining its desirable mode of operation.

To the accomplishment of this object a feature of the present invention contemplates the provision of a tape-applying machine in which the pull-off drum, provided with the ratchet, is mounted independently of the lever which oscillates and reciprocates the tape-applying mechanism to which lever the pawl is operatively connected, the ratchet being movable periodically into engagement with the pawl whereby the combined oscillating and reciprocating movement of the lever causes the pawl through the ratchet to rotate the drum. Thus, the lever is relieved of the duty of carrying the heavy drum and ratchet resulting in a more satisfactory operation of the tape-applying mechanism.

Other features of the present invention consist in certain devices, combinations and arrangement of parts hereinafter described and then set forth broadly and in detail in the appended claims which possess advantages readily apparent to those skilled in the art.

The various features of the present invention will be understood readily from an inspection of the accompanying drawings illustrating the best form of the present invention known to the inventor, in which:

Figure 1 is a view in right side elevation of the tape-applying machine;

Fig. 2 is a view in front elevation;

Fig. 3 is a detail view in front sectional elevation, the tape-severing knife being latched in its inoperative position;

Fig. 4 is a view similar to Fig. 3, the tape-severing knife being engaged with the cutting block;

Fig. 9 is a detail view in plan, and

Fig. 10 is a detail view in sectional plan on the line 10—10, Fig. 1.

Generally, the illustrated embodiment of the present invention is provided with a tape-applying mechanism, a pair of work-supporting rolls, a device for pulling tape from the main tape source of supply and for forming a slack tape source of supply from which the tape-applying mechanism withdraws tape free from the main source of supply tension as needed, a tape-severing knife, a tape-guide, and a tape-presenter to feed the leading edge of the tape from the point of cut-off into the zone of activity of the tape-applying mechanism.

The applying of the tape to the work is accomplished by the combined action of the two work-supporting rolls 12 and 13, (Figs. 2, 3 and 4) and a pressing member or hammer 14.

The pressing member 14 is detachably connected to the bottom of a head member 15, or lever, which has a vertical movement and also a rocking movement laterally. The oscillating head 15 is mounted on the main frame 16 of the machine and it receives its oscillating movement from an eccentric, (not shown), on a driving shaft 17 carried by the main frame. The head 15 is provided with a slot 18, (Figs. 2, 3 and 4), through which extends a stud 19 fast on the main frame 16, said stud having a block 20, which is mounted in the slot 18 and is journaled on the stud 19.

As the shaft 17 is rotated the eccentric thereon gives the head 15 an up-and-down movement and also a rocking movement laterally, said movements causing the face of the pressing member 14 to move toward and from the work on the work support and also to have a lateral rocking contact with the work.

In the machine disclosed in the patent to Osgood, No. 1,549,376, the head, corresponding to the head 15, slides on the block in a direction radial to the eccentric pin or strap during the rotation of the eccentric, that is, in a straight line which intersects both the axis of the shaft and the center of the stud. With this construction the right-hand corner of the hammer, viewing the front of the machine, passes through an orbital path which differs from the path passed through by a regular four motion device, having equal up-and-down and equal lateral steps, in that the square corners thereof are rounded. With such a mode of operation the right-hand corner of the hammer, in passing from the vertical to the horizontal transverses a curve in the path and thus imparts a glancing blow to the work at the moment of initial impact.

In the illustrated embodiment of the present invention, the head 15 slides on the block 20 in a direction non-radial to the eccentric during its rotation, that is, in a straight line which extends downwardly and laterally towards the toe of the hammer across the straight line intersecting the axis of the shaft 17 and the center of the stud 19. With this construction and mode of operation the hammer has a compound movement during its descent into contact with the work. That is, the hammer in moving downwardly also moves forwardly in a direction opposed to the line of feed.

The work-supporting rolls 12 and 13 each comprise a rubber ring 21 carried by a metallic ring 22 which is freely rotatable upon a stud 23 projecting forwardly from a block 24. The rear face of the block 24 (Fig. 5) is provided with a way 25 which receives a cross-bar 26 secured to the front end

of a carrier 27. The block 24 is provided with ears 28 and 29 (Fig. 3) each of which is slotted to embrace the shank of a headed-screw 30 threaded into a hole 31 (Fig. 5) topped into the cross-bar 26 thus to permit the position of the block 24 on the carrier 27 to be varied laterally.

The carrier 27 supports a conventional work guide (not shown). The rear end of the carrier 27 is pivoted at 32 from the walls of a hollow frusto-conical domed shell 33, (Fig. 1), connected to the frame 16 through a vertical web 34.

The front end of the carrier 27 is pivoted also to the arms of a yoke 35 constituting, in effect, one link of a toggle, (Fig. 1). The other link 36 of the toggle comprises a yoke which is rotatably mounted on a horizontal rod 37 carried by the base of the shell 33. The floating pivot for the toggle links 35 and 36 is formed by a pair of conical ended screws 38 carried by the link 36 and arranged to engage conical cavities formed in the lateral sides of the yoke 35.

In order to force the work-supporting rolls 12 and 13 upwardly towards the tape-pressing member 14 yieldingly, the back face of the yoke 35 is provided with a pair of spaced arms 39, (Fig. 1), which support a horizontal rod 40 upon which a block 41 is pivotally mounted. The block 41 receives one end of a screw-threaded rod 42 the other end of which is provided with a nut 43 threaded into the shell 33 and provided with a spring tension adjusting hand wheel 44. Coiled around the rod 42 and interposed between collars 45 and 46 thereon is a spring 47.

In order to break the toggle and thus lower the work-supporting rolls 12 and 13 to facilitate the insertion and removal of the work into and out of the machine, respectively, the link 36 is provided with an arm 48, (Fig. 2) which is pivotally connected to the upper end of a treadle rod 49. The dome of the shell 33 is provided with an adjustable bolt 50, (Fig. 2), the lower end of which is arranged to engage a vertical extension 51 on the carrier 27 and thus act as a stop to limit the upward movement of the work-supporting rolls under the influence of the spring 47.

As usual in this type of machine the tape is coiled in a coil 52 (Fig. 2) which is supported from the rod 53 carried by the dome 33, in a conventional manner. The roll 52 constitutes the main source of tape-supply. From the source of supply the tape passes under a drum 54 the longitudinally-milled peripheral surface of which engages the sticky face of the tape. The drum 54 is loosely mounted on a stud 55 which projects forwardly from an arm 56 pivoted on a horizontal rod 57. The rod 57 is secured to a bracket 58 (Fig. 2) secured to the frame 16.

One face of the drum 54 is provided with a ratchet 59 which is held from movement in a clockwise direction by a pawl 60. The pawl 60 is loosely mounted on a stud 61 secured to a bracket 62 on the arm 56. The pawl 60 is held engaged with the ratchet 59 by a spring 63 (Fig. 9) coiled about the stud 61, one end of the spring being hooked into the pawl 60 and the other end of the spring being hooked into the bracket 62.

From the drum 54 the tape passes over a take-up roll or feeler 64 the concave peripheral surface of which engages the non-tacky face of the tape. The take-up roll is loosely mounted on a stud 65 projecting forwardly from the free end of the arm 56. The arm 56 is held normally engaged with a stop 66 on the bracket 58 by a spring 67, coiled about the rod 57, one end of the spring being hooked into the arm 56 and the other end of the

the spring being hooked into a collar 68 secured to the rod 57. The spring 67 holds normally the drum 54 and the feeler roll 64 in their extreme positions of elevation.

5 From the feeler roll 64 the tape is conducted to the zone of activity of the hammer by a tape-guide 69 (Fig. 8) the upper end of which is loosely mounted on a horizontal stud 70 projecting forwardly from the frame 16. The back face of the 10 tape-guide, illustrated in the left-hand view of Fig. 8, is provided with a slot 71 to enable the free end of a leaf-spring 72 secured to the back face to engage the non-tacky face of the tape and press it under a mild tension against an internal 15 surface 73 associated with the front face of the tape-guide. The front face of the tape-guide is provided with a flat surface 74 terminating at one side in a wall 75. The surface 73 is integral with the wall 75, the construction being such as to 20 provide an elongated opening 76, (Fig. 8) between the surfaces 73 and 74 to facilitate the threading of the tape into the tape-guide. During its 25 passage through the tape-guide the tape is held from displacement laterally in one direction by the wall 75 and in the other direction by a gage block 77 secured in a blind opening 78 formed in the side of the tape-guide just above the opening 76. The tape emerges from beneath the surface 73 of the tape-guide through an opening 79 formed 30 by a block 80 secured to the surface 74 in spaced relation to the lower end of the surface 73. The upper edge of the block 80 is beveled at 81 (Fig. 8) to ease the passage of the tape thereover.

The block 80 of the tape-guide during the tape-applying operation is held just above the cutting-bed surface 82 of a cutting block 83 secured to the web 34. The block 83 is provided with an inclined guideway 84 which conducts the tape to the zone of activity of the hammer.

40 From the construction described it is apparent, as the drum 54 is free to rotate in a contra-clockwise direction, viewing Fig. 2, that during the feed of the work over the rolls 12 and 13 by the hammer 14 there is a tendency for the hammer to pull tape from the coil 52 at each feeding step. 45 But, as the tacky face of the tape in the coil 52 is stuck to an adjacent face in an adjacent convolution, considerable force is required to unwind the tape from the coil. It is, therefore, undesirable to rely upon the hammer to pull tape from the source of supply as the pulling force exerted thereby would drum-head the tape between the work and the block 83 and thus interfere with the application of the tape to the work.

55 In the illustrated embodiment of the present invention the drum 54 is rotated in a manner presently to be described to unwind the tape from the coil 52 and to produce an auxiliary supply of slack tape which is used up as needed by the 60 hammer 14.

The drum 54 is rotated by a pawl 85 pivoted upon a link 86. The pawl 85 is held normally against a stop 87 on the link 86 by a coiled spring 870, one end of which is secured to a pin on the 65 link and the other end of which is secured to a pin on the pawl. The upper end of the link 86 is pivoted upon a stud 88 projecting forward from the upper end of the bracket 58. The lower end of the link 86 is pivoted to one end of a link 89 the other end of which is pivoted on a stud 90 70 secured to an ear 91 on the head 15. With this construction the pawl 85 moves in an oscillating path during the inclined reciprocation and lateral oscillation of the head 15.

75 Fig. 2 shows the pawl 85 withdrawn from the

ratchet 59 on the drum 54. This is due to the position of the take-up or feeler roll 64 which is held in engagement with the loop of withdrawn tape by the light spring 67. In consequence no tape is pulled from the source of supply by the drum 54 which is stationary during the operation of the tape-applying hammer 14. As the slack in the loop of withdrawn tape engaged by the feeler 64 is used up the feeler 64 is moved downwardly by the tape under the influence of the hammer 14 against the tension of the light spring 67 until the ratchet 59 on the drum 54 is moved into the oscillating path of the pawl 85. Then the pawl 85 rotates the ratchet 59 and the drum 54 in a contra-clockwise direction, (Fig. 2), to 10 draw tape from the source of supply.

In the illustrated embodiment of the invention the stroke of the pull-off drum 54 is such that more tape is pulled from the source of supply than is used up by the hammer 14 in a single feeding step thereof. With such a construction and mode of operation the withdrawn tape is bound to accumulate. But as the spring 67 maintains the feeler 64 engaged with the withdrawn tape during its accumulation the drum 54 is withdrawn from the oscillating path of the pawl 85 and the operation of the tape pull-off drum 54 suspended.

When the hammer 14 eats into the accumulation of withdrawn tape the ratchet 59 on the drum 54 is replaced in the oscillating path of the pawl 85 and the drum 54 is rotated again to withdraw more tape. In the preferred mode of operation the pull-off operates in timed relation with the hammer 14 during successive cycles 35 varying in number, depending upon prevailing conditions and then the operation of the pull-off is suspended for one cycle, or it may be, successive cycles depending again on the prevailing conditions. Thus, while the hammer 14 is operated 40 periodically the pull-off is operated non-periodically.

It is usual in this type of tape-applying machine to provide a tape-severing knife to sever the tape. In the illustrated embodiment of the 45 invention the tape-severing knife 92 is formed upon the bottom of a plate 93 mounted to slide vertically. To this end a block 94 (Fig. 1) is secured to the web 34. The block 94 (Fig. 10) is milled vertically to provide a way 95 for the 50 plate 93, the front end of the milled slot being filled by a filling piece 96. The plate 93 near its upper end is secured to a block 97 which is carried by the lower end of a rod 98 mounted to slide vertically in a block 99 secured to a bracket 100 55 carried by the machine frame 16.

The tape-severing knife 92 is actuated to sever the tape by a spring 101 coiled about the rod 98 and interposed between a washer 102 engaged with the block 97 and a washer 103 engaged with the block 99. To store power in the spring 101 one face of the block 94 is provided with a slide 104 which slides beneath cover plates 105 and 106 secured to the block 94. The slide 104 is provided with a pin 105' having peripheral surfaces of different diameters, the smaller one of which is pivoted to one end of a link 107 the other end of which is pivoted to an arm 108 projecting forwardly from one end of a rock shaft 109, journalled in a bracket 110 (Fig. 1) bolted to the web 70 34. The other end of the rock shaft 109 is provided with an arm 111 which is pivotally connected to the upper end of a treadle-controlled rod 112 (Fig. 2), which slides freely either through the bench upon which the machine is 75

mounted or the base of the dome 33 as indicated. When the treadle-controlled rod 112 is depressed power is stored in a spring 113 coiled about the rod and interposed between the stationary part 6 through which the rod slides and a collar 114 secured to the rod to restore the rod to its initial elevated position upon release of the treadle.

When the treadle-controlled rod 112 is depressed both the slide 104 and the pin 105 engage 10 the bottom of the block 97 and elevate the tape-severing knife from the position of Fig. 4 to that of Fig. 3 in which position the knife is latched against the stored power of the spring 101. To this end the upper end of the plate 93 is provided 15 with an opening 115 arranged to receive a latch 116 formed on an arm 117 depending from a rock-shaft 118 journaled on the bracket 100.

Near its rear end the rock-shaft 118 is provided with an arm 119 which is pivoted to the upper 20 end of a link 120, the lower end of which is pivoted on a stud 121 secured centrally to an operating lever 122. One end of the operating lever 122 is pivoted on a pin 123 carried by the block 94. The other end of the lever 122 is provided 25 with a finger-piece 124. The latch 116 is rocked into the position of Fig. 3 by a coiled spring 125, (Fig. 2), one end of which is hooked into a pin on the bracket 100 and the other end of which is hooked into a pin on the link 120.

30 With the construction described, depression of the treadle controlled rod 112 elevates the tape-severing knife, stores power in the knife-operating spring and locates the opening 115 in position to receive the latch 116 thus to hold the knife in readiness for the tape-severing operation. To 35 actuate the tape-severing knife the operative presses the finger-piece 124 thereby withdrawing the latch 116 from the opening 115 to release the tape-severing knife to the influence of the 40 stored-power in the spring 101 which drives the knife downwardly to sever the tape on the cutting bed surface 82.

From an inspection of Figs. 3 and 4 it is apparent that during the normal tape-applying 45 operation the lower end of the tape-guide 69 is interposed between the tape-severing knife and the cutting-bed surface. In order to move the lower end of the tape-guide out of the path of movement of the tape-severing knife and to lay 50 the tape over the cutting-bed surface 82 when the finger-piece 124 is operated to release the knife for its tape-severing stroke the lower end of the wall 75 on the tape-guide 69 is provided with a pin 126 upon which the lower end of a link 127 is pivoted. The upper end of the link 55 127 is pivoted on the stud 121 carried by the operating lever 122.

The operating lever 122 and the parts operated therefrom including the latch 116 and the 60 tape-guide 69 are locked in the position of Fig. 4 against the tension of the spring 125 by a pin 128 carried by a block 129 secured to the upper end of the rod 98. The pin 128, during the tape-severing operation rides along one edge of an 65 arm 130 which is secured to the rock-shaft 118 by a split-clamp fastening. In order that the operating positions of the tape-guide 69 and the latch 116 may be correlated accurately the link 120 is made in two parts (Fig. 5) which are 70 justably connected in order that the length of the link 120 may be varied slightly. The block 94 is provided with a yoke 131, the arms of which are arranged upon opposite sides of a stud 132 carried by the lower part of the two part link 75 120. The yoke 13 is adjustably secured to the

block 94, (Fig. 1). When the parts are in the position of Fig. 3, the stud 132 should engage the lowermost arm of the yoke 130 and the bottom of the upper part of the two-part link 120 should engage the uppermost arm of the link 130. 5

In order to bring the leading edge of the tape connected to the source of supply from the position it occupies when formed by the tape-severing knife down the face 83 of the cutting block and through the guideway 84 into the zone of 10 activity of the tape-applying hammer 14, the slide 104 is provided with a tape-presenter 133. The tape-presenter 133 comprises a thin plate, the upper end of which is secured flat-wise to the slide 104. The lower end of the tape-presenter 15 133 projects below the slide 104 which projecting portion is bent downwardly and to the left, viewing Fig. 4, to cause the tape-presenter to engage the tape passing through the guideway 84. The lower end of the tape-presenter engages 20 the tacky face of the tape adjacent its leading edge and drags it from the cutting block to the zone of activity of the hammer 14.

Fig. 4 illustrates the position of the tape-guide, the tape-severing knife and the tape-presenter 25 at the completion of the tape-severing operation. When the operative depresses the treadle-controlled rod 112 the tape-severing knife and the tape-guide are moved from the position of Fig. 4 to that of Fig. 3. The tape-severing knife is elevated when the slide 104 which carries the tape-presenter is elevated from the treadle-controlled rod 112. The tape-guide is moved from the position of Fig. 4 to that of Fig. 3 by the spring 125 when the pin 128, during the upward 30 movement of the rod 98, rides off the end of the arm 130. During this movement of the tape-guide the freshly cut leading edge of the tape is caused to dangle over the edge of the cutting-bed surface 82. When the slide 104 is elevated 35 the lower end of the tape-presenter is elevated into engagement with the exterior surface 73 on the tape-guide. Then, when the treadle-rod 112 is released the spring 113 causes the lower end of the tape-presenter to wipe downwardly 40 over the tape-guide from which it picks up the tape adjacent the leading edge thereof and moves it downwardly into the guideway 84 from the lower end of which the leading edge of the tape 45 dangles so that when the new piece of work is 50 introduced into the machine the leading edge is brought beneath the hammer 14.

From an inspection of Fig. 3 it is apparent that the hammer 14 cooperates first with the work-supporting roll 12 to feed the leading edge 55 of the work in the direction of the arrow over the periphery of the roll 12. The hammer then cooperates with both of the rolls 12 and 13 to feed the work over their peripheries and to bend that portion of the work which bridges the peripheries of the rolls 12 and 13 about an axis extending substantially normal to the line of feed. The hammer then cooperates with the roll 13 to feed the trailing edge of the work over its periphery. During the feed of the work the rolls are rotated in a contra-clockwise direction, viewing Fig. 3, so that the hammer cooperates with the down-going side of the roll 12 and the up-going side of the roll 13. As shown in Figs. 50 3 and 4 the bottom of the hammer is elongated to bridge the gap between the rolls, is concaved from toe to heel to fit the concavity produced in the work by bending the portion of the work 55 extending unsupported between the peripheries 75

of the rolls, and has its toe grooved laterally to provide sharp lands to facilitate the initial engagement of the tape with the work and its subsequent feed.

5 In order to prevent the leading edge of the work from following the down-going side of the roll 12 the block 24 is provided with a strip 134 (Figs. 3 and 4) having a vertical portion which is secured to the block and an upper horizontal 10 guard portion 135 which extends between the peripheries of the rolls 12 and 13 longitudinally thereof. As shown in Figs. 3 and 4 the lateral edges of the guard portion 135 are bevelled to enable the edges to extend close to the peripheries of the rolls.

15 Nothing herein explained is to be interpreted as limiting the various features of the present invention in the scope of its application to use in connection with the particular machine or 20 the particular mode of operation or any combination thereof selected for purposes of illustration and explanation. While the particulars of construction herein set forth are well suited to one mechanical form of the invention and to 25 the uses to which it is put, it is not limited as to these uses, nor to these details of construction, nor to the conjoint use of all its features, nor is it to be understood that these particulars are essential since they may be modified within the 30 skill of the artisan without departing from the true scope of the actual invention, characterizing features of which are set forth in the following claims by the intentional use of generic terms and expressions inclusive of various modifications.

35 What is claimed as new, is:

1. A tape-applying machine having, in combination, means for supporting the grain or finished face of the work, and means cooperating therewith for feeding the work, for bending the flesh or unfinished face of the work concavely about an axis extending substantially normal to the line of feed, and for applying tape to the bent face.

45 2. A tape-applying machine having, in combination, means for supporting the work and a single means cooperating therewith for feeding the work, for bending the flesh or unfinished face of the grain or finished face of the work concavely about an axis extending substantially 50 normal to the line of feed and for applying tape to the bent face.

55 3. A tape-applying machine having, in combination, means for supporting the grain or finished face of the work, and means cooperating therewith for feeding the work progressively, for bending progressively the flesh or unfinished face of the work concavely about an axis extending substantially normal to the line of feed, and 60 for applying tape progressively to the bent face.

4. A tape-applying machine having, in combination, means for supporting the work comprising a pair of spaced apart rolls and a tape-applying means constructed and arranged to bridge the space between the rolls and engage at least a portion of the work extending unsupported between the rolls.

5. A tape-applying machine having, in combination, means for supporting the work comprising a pair of spaced apart rolls, and a tape-applying means constructed, arranged and operated to cooperate first with one of the rolls only, then with both rolls, and finally with the other one of the rolls only during each cycle 75 of operation.

6. A tape-applying machine having, in combination, a pair of spaced apart, freely revoluble rolls, and a tape-applying means cooperating therewith to feed the work and thereby rotate the rolls, the tape-applying means cooperating with the down-going side of one roll and the up-going side of the other roll.

7. A tape-applying machine having, in combination, means for supporting the work comprising a pair of spaced apart rolls and a tape- 10 applying means constructed and arranged to bridge the space between the rolls and engage at least a portion of the work extending unsupported between the rolls, and means for preventing the work from passing through the space 15 between the rolls.

8. A tape-applying machine having, in combination, a pair of spaced apart work-supporting rolls, a guard extending between the rolls, and a tape-applying hammer mounted above the 20 guard to feed the work thereover and the peripheries of both rolls.

9. A tape-applying machine having, in combination, a pair of work-supporting rolls, a tape- 25 applying means cooperating with the rolls to tape the work, a common support for the rolls, a carrier and means for connecting the support adjustably to the carrier.

10. A tape-applying machine having, in combination, a source of tape-supply, a moving lever, 30 a pawl operatively connected thereto, a drum, engaged with the portion of the tape extending from the source of supply, a ratchet for rotating the drum, and means for moving the ratchet into engagement with the pawl, whereby movement of the lever causes the pawl to rotate the 35 ratchet.

11. A tape-applying machine having, in combination, a source of tape-supply, a lever, a pivot therefor, means for oscillating the lever on its 40 pivot and for reciprocating the lever, a drum, engaging that portion of the tape extending from the source of supply, mounted independently of the lever, a ratchet for rotating the drum, a pawl operatively connected to the lever, 45 and means for moving the ratchet into engagement with the pawl, whereby the combined oscillating and reciprocating movements of the lever causes the pawl through the ratchet to rotate the drum.

50 12. A tape-applying machine having, in combination, a source of tape-supply, a lever, a pivot therefor, means for oscillating the lever on its pivot and for reciprocating the lever, linkage one end of which is pivoted on a stationary part 55 and the other end of which is pivoted on the lever, a pawl carried by the linkage, a pivoted carrier, a drum, engaging that portion of the tape extending from the source of supply, and a feeler carried thereby, a ratchet for rotating 60 the drum, means for maintaining the carrier normally elevated, and means acting through the feeler to depress the carrier and move the ratchet into engagement with the pawl, whereby the combined oscillating and reciprocating movements of the lever causes the pawl through the ratchet to rotate the drum.

65 13. A tape-applying machine having, in combination, a tape-applying mechanism, tape-severing mechanism, a cutting bed surface, a 70 tape-guide having its tape-delivering end interposed between the tape-severing mechanism and the cutting-bed surface, means for throwing the tape-severing mechanism out of operation, a latch for retaining the tape-severing mecha- 75

nism out of operation and means for tripping the latch and for withdrawing the tape guide from the path of movement of the tape-severing mechanism.

- 5 14. A tape-applying machine having, in combination, tape-applying mechanism, tape-severing mechanism, a cutting bed surface, a tape-guide having its tape-delivering end interposed between the tape-severing mechanism and the cutting bed surface, means for throwing the tape-severing mechanism out of operation and for feeding the freshly cut leading edge of the tape from the point of cut-off into the zone of activity of the tape-applying mechanism, a latch for 10 retaining the tape-severing mechanism out of operation and means for tripping the latch and for withdrawing the tape guide from the path of movement of the tape-severing mechanism.
- 15 15. In a tape-applying machine the combination with a tape-severing knife, an independent slide and a tape-presenter carried thereby, of means for operating the slide in one direction to throw the tape-severing mechanism out of operation and in the opposite direction to cause 20

the tape-presenter to engage and feed the freshly cut leading edge of the tape.

16. A tape-applying machine having, in combination, a tape-severing mechanism, a latch for retaining it out of operation, a tape-guide 5 movable into and out of the path of movement of the tape-severing mechanism, a common spring for moving the latch and the tape-guide in one direction and means for moving the latch and the tape-guide in the opposite direction. 10

17. A tape-applying machine having, in combination, a tape-severing mechanism, a latch for retaining it out of operation, a tape-guide movable into and out of the path of movement of the tape-severing mechanism, a common spring 15 for moving the latch and the tape guide in one direction and means for moving the latch and the tape guide in the opposite direction, a latching means for locking the latch and tape guide from movement under the influence of the common spring, and means for unlocking the latching means and for throwing the tape-severing mechanism out of operation. 20

WALTER P. OSGOOD.
